PLATEN CONTROL DEVICE

Paul E. Flowers, Mount Gilead, Ohio, assignor to
 The Hydraulic Development Corporation, Inc.,
 Wilmington, Del., a corporation of Delaware

Application May 7, 1941, Serial No. 392,319

6 Claims. (Cl. 60—52)

This invention relates to hydraulic presses and, in particular, to controlling mechanisms for the manual control of press platens.

Such controlling mechanisms as heretofore known consisted substantially of a hand wheel operated spindle connected by a linkage with the flow control member of a hydraulic pump supplying pressure fluid for actuating the press platen. While these known controlling mechanisms are quite satisfactory for the purpose of setting up a press for the intended work, they do not meet the requirements of modern industries as to speed and flexibility in operation. In particular, they do not allow fast traverse movement of the press platen.

Accordingly, it is an object of the invention to provide a manually operable controlling mechanism for the platen of a press which, although simple in construction, will overcome the drawbacks above referred to in connection with platen controlling mechanisms heretofore known.

It is another object to provide a manually operable controlling mechanism which will make it possible to raise and lower the platen of a press rapidly, and also absolutely and instantly to control the movement of the press platen after it has contacted the work piece.

A further object of the invention consists in the provision of a controlling mechanism in which a simple shifting movement of a hand lever may at any time during a pressing cycle bring the press platen instantly to a stop or to cause a fast or slowed down movement of the platen in either direction of its movement.

It is still another object of the invention to provide a controlling mechanism of the type set forth in the preceding paragraph, in which the press platen may be caused to move a predetermined distance by merely shifting the hand lever through a predetermined angle.

These and other objects and advantages of the invention will appear more clearly from the following specification in connection with the accompanying drawings, in which:

Figure 1 is a view of a press provided with the controlling mechanism according to the present invention.

Figure 2 diagrammatically illustrates the hydraulic circuit for the controlling mechanism of the invention.

Figures 3 and 4 illustrate in different positions a control cylinder forming part of the controlling mechanism according to the invention.

Figure 5 shows the hand lever of the controlling mechanism.

General arrangement

The controlling mechanism of the present invention substantially comprises a hand lever operatively connected by a linkage on one hand with

the flow control member of a variable delivery pump supplying pressure fluid for advancing the press platen and, on the other hand, with a fluid containing control cylinder communicating with the fluid tank of the press and having reciprocably mounted therein a plunger connected with the press platen. Communication of the fluid tank and the control cylinder is controlled by a normally open valve adapted to be closed by the hand lever.

By shifting the hand lever and maintaining the valve open, fast movement of the platen may be obtained in either direction, whereas when the valve is closed, shifting movement of the hand lever is adapted to cause slow movement of the platen in the desired direction.

Structural arrangement

The press shown in the drawings comprises a press bed 1 and a press head 2 connected with each other by means of a column or frame 3. The press head 2 comprises a press cylinder 4 having reciprocably mounted therein a double-acting press piston 5 with a piston rod 6 connected to the press platen 7.

The cylinder 4 is adapted to communicate through a surge valve 8 with a fluid reservoir or surge tank 9 mounted on top of the press head 2. Arranged in the tank 9 is a main cylinder release and pump by-pass valve 10, which is adapted to communicate through conduits 11 and 12 with the surge valve 8.

The surge valve 8 and the main cylinder release and pump by-pass valve 10 do not form a part of the present invention and for a more detailed description thereof reference may respectively be had to U. S. Patent No. 2,193,248 and U. S. Patent No. 2,268,205.

The purpose of the surge valve consists in prefilling the press cylinder 4 when the press piston 5 moves downwardly by gravity, while the main cylinder release and pump by-pass valve 10 is provided for the purpose of relieving the pressure on the piston 5 for facilitating the initiation of the retraction stroke of the platen 7.

Also connected with the main cylinder release and pump by-pass valve 10 is a conduit 13 leading to a conduit 14, which on one hand communicates with the upper portion of the press cylinder 4, and on the other hand leads to a balancing cylinder 15, having mounted therein the balancing plunger 16 connected with the press bed 1. The balancing cylinder and plunger system 15, 16, which serves to prevent undue bending of the press head relative to the press frame and press bed, likewise does not form a part of the present invention, and is fully described in U. S. Patent No. 2,296,051.

Furthermore connected with the valve 10 is a conduit 17 leading to the conduit 13. A check

valve 18 connected with the conduit 12 is provided for admitting fluid from the tank 9 into the conduit 12, which communicates with the lower portion of the press cylinder 4 and is connected by a branch line 19 with one side of the variable delivery pump 20. The other side of the variable delivery pump 20 is connected with the upper portion of the press cylinder 4 through a conduit 59. The variable delivery pump 20 may be of any standard type, preferably of the type set forth in U. S. Patent No. 2,184,665.

The flow control member (not shown) of the pump 20 and, thereby, the delivery and direction of delivery of the pump is controlled by the valve rod 21 which is pivotally connected by a link system, generally designated 22, with a bell crank lever 23 shiftable about the pivot 24 and adapted to engage a collar 25 adjustably mounted on a push rod 26. Also adjustably mounted on the push rod 26 is a collar 27 adapted to be engaged by the arm 28 connected to the platen 7. Also connected with the platen arm 28 is a plunger 29 reciprocably mounted in a control cylinder 30 and passing through packing material 31 and a gland 32 connected with the upper portion of the control cylinder 30.

The control cylinder 30 is slidably mounted in guiding members 33 and 34, which are connected to the column or frame 3. The lower side of the guiding member 33 is engaged by a spring 35, the lower end of which is supported by a collar 36 adjustably mounted on the control cylinder 30 by means of an adjusting screw 37. A spring 38, preferably identical to the spring 35, is mounted between the guiding member 34 and a collar 39 likewise adjustably mounted on the control cylinder 30. The springs 35 and 38 tend to hold the control cylinder 30 in an intermediate position. The space between the collars 36 and 39 is engaged by a fork-shaped portion of a lever arm 40 carrying a pivot 62 which is slidably engaged by the forked portion 63 at the lower end of the push rod 26. The length of the forked portion 63 is such that the pivot 62 is always engaged thereby, even when the pivot 62 is in its lowermost position and the push rod 26 is in its uppermost position.

The lever arm 40 is pivotally connected with a link 41, which in its turn is pivotally connected to a lever 42 shiftable about the pivot 43. The other end of the lever 42 is linked to a link 44, which in its turn is pivotally connected to an arm 45 rotatably connected with a shaft 46 (Figure 5). The front end of the shaft 46 is slotted and has mounted therein a control lever 47 shiftable about a pin 48 extending across the slot 49 in the shaft 46.

The lower end of the control lever 47 broadens out into a contact member 50 which is adapted to engage a normally open switch 51 so as to cause the latter to close the energizing circuit for the solenoid 52 which, when energized, closes the shutoff valve 53 adapted to effect or interrupt hydraulic communication between the flexible conduit 54 connected with the lower portion of the control cylinder 30 and the conduit 55 leading to the tank 9. The valve 53 in its normal or open position allows fluid from the tank 9 to fill the control cylinder 30 so that the latter is normally filled with fluid.

As will be clear from Figure 5, the control lever 47 may selectively be shifted toward the right or the left without actuating the switch 51. If desired, the control lever 47 may also be shifted about the pin 48 so as to close the switch 51 and

then toward the left or the right, while maintaining the switch 51 closed. The control lever 47 is connected to two centering springs 56, 57, which tend to disengage the control lever 47 from the switch 51, and to return the control lever 47 into the position shown in Figure 2.

To enable the operator to control the angle through which the control lever 47 is shifted, a calibrated scale 58 may be provided.

Operation

Suppose that all parts of the press occupy the position shown in Figures 1 and 2, and that it is now desired to start a pressing cycle. To this end, the operator shifts the control lever 47 toward the left, for instance, into the left position indicated in Figure 4, without shifting the lever 47 about the pin 48.

As a result of this movement the shaft 46 is rotated in anti-clockwise direction, thereby causing the lever arm 40 to shift about the front end thereof as a pivot into the position of Figure 3, which movement in its turn causes upward movement of the push rod 26, thereby shifting the valve rod 21 toward the right with regard to Figures 1 and 2. As a result thereof, the pump 20 is shifted into forward stroke position and delivers fluid through the conduit 59 into the upper portion of the press cylinder 4, while withdrawing fluid from the lower portion of the press cylinder 4 through the conduit 19. The platen 7, therefore, moves downwardly by gravity as fast as fluid is withdrawn from the lower portion of the press cylinder 4, while the fluid delivered by the pump 20 into the upper portion of the press cylinder 4 is supplemented by fluid from the tank and passing through the surge valve 8. In this way, fast traverse movement of the platen 7 is obtained by a single shifting movement of the control lever 47.

While the platen 7 thus slides downwardly, the plunger 29 enters the control cylinder 30 and expels fluid therefrom, which flows through conduit 54, shutoff valve 53 and conduit 55 into the tank 9. Since no force is acting on the control cylinder 30 and the centering springs 35 and 38 maintain the cylinder 30 in intermediate position, no movement of the control cylinder 30 takes place.

Supposing now that the press platen 7 approaches the work piece, and that it is desired to slow down the platen movement. To this end the operator does not return the control lever 47 to its starting position, but shifts the latter from its present position about the pin 48, so that the contact member 50 of the control lever 47 engages the switch 51 and closes the same, thereby energizing the solenoid 52. Energization of the solenoid 52 closes the shutoff valve 53 which in its turn now interrupts communication between the fluid tank 9 and the control cylinder 30. Inasmuch as no fluid can now escape from the control cylinder 30 while the downward movement of the plunger 29 continues, the pressure exerted upon the fluid entrapped in the control cylinder 30 acts upon the latter and moves the control cylinder 30 downwardly against the thrust of the centering spring 38. While the control cylinder 30 thus moves downwardly, the arm 40 shifts about the pivot 60 connecting the link 41 with the arm 40 in anti-clockwise direction so that the push rod 26 is moved downwardly by the bell crank lever 23 which is continuously urged against the collar 25 by the link system 22 acted upon by a spring in the servomotor 61 of

the variable delivery pump 20. As a result, the valve rod 21 is shifted toward the left with regard to Figures 1 and 2, thereby moving the pump 20 to neutral or no delivery position.

The press platen, therefore, gradually decreases its downward speed and if the control lever 47 is held in the position into which it was last shifted, the platen 7 comes to a standstill. It should be noted that, although the pump 20 is now in its neutral position, the control lever 47 is not in its vertical position shown in Figure 2, but in an inclined position and, similarly, the lever arm 40 is inclined, while the spring 38 is compressed as shown in Fig. 4.

If it is now desired to slowly move the platen 7 further downwardly to effect a pressing operation, the control lever 47 is further shifted toward the left. As the press platen 7 had previously come to a standstill, it will be clear that the last mentioned further leftward movement of the control lever 47 causes the arm 40 to shift in anti-clockwise direction about the left end of the arm 40, since, at this time, the cylinder 30 is stationary. Consequently, the push rod 26 is lifted and the valve rod 21 is moved toward the right so as to place the pump again on forward stroke position.

The platen 7, therefore, is moved downwardly by pressure fluid delivered from the pump 20 into the upper portion of the press cylinder 4 and, in the same manner as previously described, the control cylinder 30 moves downwardly until the arm 40 has shifted in anti-clockwise direction about the pivot 60 to such an extent that downward movement of the push rod 26 has enabled the valve rod 21 to return to its previous position shown in Figure 2, in which the pump 20 is in neutral or no delivery position so that the platen 7 again comes to a halt.

In this way a gradual inching movement of the platen 7 can be obtained, and it will be clear that a leftward movement of the control lever 47 by a predetermined degree causes the platen 7 to advance by a predetermined extent, provided, of course, that the contact member 50 of the control lever 47 holds the switch 51 closed. In other words, the operator can obtain a predetermined movement of the press platen by shifting the control lever through a predetermined angle.

If, for some reason, a slight and slow retraction movement of the platen 7 is desired, the operator merely shifts the control lever 47 from the position in which the platen 7 last came to a standstill toward the right, thereby moving the push rod 26 downwardly and the valve rod 21 further toward the left beyond the position shown in Figure 1, which puts the pump 20 on retraction stroke. Pressure fluid is then delivered by the pump 20 through conduit 19 into the lower portion of the press cylinder 4, while fluid is withdrawn from the upper portion of the press cylinder 4 to the pump 20.

The platen 7 and, consequently, also the plunger 29 now move upwardly and, inasmuch as the shutoff valve 53 is still closed, the pressure in the control cylinder 30 is relieved so that the spring 38 acting upon the collar 39 causes the control cylinder 30 to follow the upward movement of the plunger 29. During this upward movement of the control cylinder 30, the lever arm 40 shifts in anti-clockwise direction about the pivot 60, thereby lifting the push rod 26 and moving the valve rod 21 toward the right.

When the valve rod 21 has reached the position shown in Figure 2, the pump 20 is again in neutral position and the press comes to a halt. The platen 7 may now again be put on forward stroke to a desired extent by shifting the lever 47 from its last position toward the left, in which case the forward movement of the platen previously described will be effected.

If it is desired to quickly return the platen 10 to its retracted position, the operator shifts the lever 47 from its present position toward its extreme right position, while the contact member 50 still engages the switch 51. When the lever 47 has reached its extreme right position, it is shifted about the pin 48 so as to release the switch 51. The release of the switch 51 causes the latter to open and, thereby, to deenergize the solenoid 52 so that the shutoff valve 53 again establishes communication between the control cylinder 30 and the fluid tank 9. As a result thereof the spring 38 lifts the control cylinder 30 to the position shown in Figure 2, while the fluid expelled from the control cylinder 30 during this lifting movement is returned through conduit 54, shutoff valve 53 and conduit 55 into the tank 9.

The movement of the control valve lever 47 to its extreme right position causes a rotation of the shaft 46 in clockwise direction and permits the 30 spring in the servomotor 61 of the pump 20 to shift the valve rod 21 to its extreme left position, while the push rod 26 is pushed downwardly. The pump 20 is then in full delivery retraction stroke position and delivers pressure fluid through 35 conduit 19 into the lower portion of the press cylinder 4 so that the platen 7 rapidly moves upwardly. When the platen 7 reaches the end of its upward movement, the platen arm 28 engages the collar 27 and lifts the push rod 26 into the 40 position of Figure 2, thereby returning the pump 20 to its neutral or no delivery position. If now the control lever 47 is released, the springs 56, 57 will return it to the position shown in Figure 2. This movement will not affect the push rod 26 45 since, at the time the push rod 26 is lifted into the position of Figure 2, and the control lever 47 is in its extreme right position, the pivot 62 is at the lower end of the forked portion 63 of the push rod 26. In other words, while the upper end of 50 the control lever 47 moves from its extreme right position to the position in Figure 2, the pivot 62 moves from the lower end of the forked portion 63 of the push rod 26 to the upper end of the forked portion 63, where it just engages the collar 55 64 of the push rod 26.

The present invention is of particular importance in connection with forging presses, such as the horn press shown in the drawings. However it is, of course, understood that the present invention is by no means limited to presses of this type.

As will be clear from the above, the controlling mechanism of the present invention enables, at any time of the cycle, complete control of the platen and makes it possible to advance the platen by predetermined minute distances, as well as to move the platen at high speed during the forward and also during the retraction stroke thereof.

It will also be clear from the foregoing description that the platen may be instantly stopped at any time of the cycle. If, for instance, the platen 7 is moving downwardly at high speed while valve 53 is open and cylinder 30 is in the position of Figure 2, it is merely necessary to return the control lever 47 to the position of Figure 2, to

move the pump 20 instantly to neutral position, thereby stopping the platen.

If the platen 7 is moving downwardly while valve 53 is closed and the control lever 47 is in the left hand position, indicated in dashed lines in Figure 1, movement of the upper end of lever 47 toward the right, while maintaining valve 53 closed, will pull the right end of the lever arm 40 downwardly while the left end of lever arm 40 is pulled downwardly by the now downwardly moving cylinder 30. As a result thereof, the spring in the pump servomotor presses push rod 26 downwardly, thereby shifting the pump 20 to neutral position and stopping the platen 7.

It will be understood that I desire to comprehend within my invention such modifications as come within the scope of the claims.

Having thus fully described my invention, what I claim as new and desire to secure by Letters Patent is:

1. In a hydraulic system, a main plunger having associated therewith fluid operable advancing and retracting means for reciprocating said plunger, a fluid source for supplying pressure fluid to said advancing and retracting means for actuating the same, control means for controlling the delivery of fluid from said fluid source to said advancing and retracting means, manually operable means operatively connected with said control means for varying the delivery of said fluid source, follow-up means operatively connected with said control means and said manually operable means for causing said plunger to stop after a predetermined travel thereof corresponding to a predetermined but variable setting of said manually operable means, said follow-up means including a movable cylinder, a piston therein connected to move in unison with said main plunger, and a valve controlling the flow of fluid to and from said cylinder whereby said cylinder will move with said plunger when said valve is in one position and will remain stationary when said valve is in another position, said follow-up means further including a lever system connecting said cylinder and said control means, said lever system being connected to operate said valve.

2. In a hydraulic press, a press plunger, a reversible variable delivery pump for supplying pressure fluid to said plunger to actuate the same, servomotor means associated with said pump for controlling the delivery and the direction of delivery of said pump, a manually operable lever mechanism connected with said servomotor means for actuating the latter, a reciprocable fluid filled cylinder, a control plunger reciprocable in said cylinder and movable in unison with said press plunger, said cylinder being operatively connected with said lever mechanism for actuating said servomotor means in response to the position of said lever mechanism and the movement of said press plunger, and valve means operable by said lever mechanism for selectively allowing or preventing escape of fluid from said cylinder during the working stroke of said press plunger, to thereby respectively prevent or establish positive driving connection between said plunger and said cylinder.

3. In a hydraulic circuit, a fluid operable main plunger, a fluid source for supplying pressure fluid to said plunger, control means for controlling the supply and the direction of flow of fluid from said fluid source to said plunger, a recipro-

cable fluid filled cylinder connected to actuate said control means, movable plunger means associated with said main plunger and cooperating with said cylinder so as selectively to vary the pressure condition of the fluid therein, valve means operable independently of said control means for selectively entrapping fluid in said cylinder or releasing fluid therefrom while said main plunger is in motion, and manually operable means operatively connected with said control means for actuating the same, said manually operable means also being adapted selectively to effect operation of said valve means.

4. In a hydraulic press, a press plunger, a fluid source to supply pressure fluid to said plunger for actuating the same, a fluid filled container reciprocably mounted on the frame of the press, a fluid storage tank on the head of the press, valve means for selectively establishing or interrupting communication between said tank and said container, a control plunger connected to said press plunger and reciprocable in said container, control means for varying the supply of pressure fluid from said fluid source to said press plunger, a link system operatively connected with said control means and said container, and a lever manually operable for selectively actuating said link system with or without simultaneously actuating said valve means.

5. In a hydraulic press, a press plunger having associated therewith fluid operable advancing and retracting means, a reversible variable delivery pump for supplying pressure fluid selectively to said advancing or retracting means, servomotor means for varying the supply of pressure fluid from said pump to said advancing and retracting means, control means for actuating said servomotor means, a fluid storage tank, a reciprocable fluid filled container connected to move said control means and having reciprocably mounted therein a control plunger connected to said press plunger, manually operable means for actuating said control means, valve means operable by said manually operable means for selectively effecting hydraulic communication between said tank and said container, and yielding means urging said container into an intermediate position and adapted to allow reciprocative movement of said container in response to the movement of said control plunger.

6. In a hydraulic press, a press platen having associated therewith fluid operable means for advancing and retracting said platen, a fluid pressure source for supplying pressure fluid to said fluid operable means for actuating the latter, controlling means for controlling the supply of pressure fluid to said fluid operable means, a fluid storage tank, a reciprocable cylinder, yielding means for continuously urging said cylinder into an intermediate position, valve means operable selectively to effect or interrupt hydraulic communication between said tank and said cylinder, a control plunger connected to said platen and reciprocable in said cylinder, link means operatively connected with said cylinder and said controlling means for actuating the latter, and a hand lever shiftable in one plane for controlling said valve means and in a second plane for actuating said link means to control the movement of said platen.

PAUL E. FLOWERS.
